Primary Examiner — Elizabeth A. Albert*(74) Attorney, Agent, or Firm* — Fross Zelnick Lehrman & Sissu, P.C.; Lawrence E. Apolzon, Esq.(57) **CLAIM**

The ornamental design for a pen, as shown and described.

DESCRIPTION

FIG. 1 is a front perspective view of a pen showing my new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken lines showing the screw in the drawings are included to show a feature that forms no part of the claimed design.

1 Claim, 4 Drawing Sheets(56)
